(57) **CLAIM**

The ornamental design for a taillight for a vehicle, as shown and described.

DESCRIPTION

This application contains subject matter related to the following co-pending U.S. design patent applications:

Application Ser. No. 29/488,972, filed Apr. 25, 2014 and entitled “Taillight for a Vehicle;” and

Application Ser. No. 29/488,973, filed Apr. 25, 2014 and entitled “Taillight for a Vehicle.”

FIG. 1 is a left perspective view of a first embodiment of a taillight for a vehicle according to the design;

FIG. 2 is a front view thereof;

FIG. 3 is a left side view thereof; and

FIG. 4 is a top view thereof;

FIG. 5 is a right perspective view of a second embodiment of the taillight for a vehicle according to the design;

FIG. 6 is a front view thereof;

FIG. 7 is a right side view thereof; and,

FIG. 8 is a top view thereof.

The broken lines in the drawings illustrate portions of the taillight for a vehicle which form no part of the claimed design. Also enclosed is a set of photographs of an embodiment of the design.
